US00D784266S

(12) **United States Design Patent** (10) Patent No.: **US D784,266 S**
(45) Date of Patent: **** Apr. 18, 2017**

(54) **LUG BLOCK OF A LINE STAB UNIT**

(71) Applicant: **ROCKWELL AUTOMATION TECHNOLOGIES, INC.**, Mayfield Heights, OH (US)

(72) Inventors: **Kenneth K. Leis**, Waukesha, WI (US); **Dean Thomas Meyer**, Oak Creek, WI (US); **Paul T. Krause**, Fredonia, WI (US); **Troy M. Bellows**, Racine, WI (US); **Thomas J. Becker**, Milwaukee, WI (US)

(73) Assignee: **ROCKWELL AUTOMATION TECHNOLOGIES, INC.**, Mayfield Heights, OH (US)

(**) Term: **15 Years**

(21) Appl. No.: **29/550,608**

(22) Filed: **Jan. 5, 2016**

Related U.S. Application Data

(60) Division of application No. 29/511,171, filed on Dec. 8, 2014, now Pat. No. Des. 749,520, which is a continuation of application No. 14/049,925, filed on Oct. 9, 2013, now Pat. No. 9,502,782.
